UNITED STATES PATENT OFFICE.

CHARLES H. WOODWARD, OF DALLAS, TEXAS.

STAMP-VENDING MACHINE.

1,195,318.

Specification of Letters Patent. Patented Aug. 22, 1916.

Application filed May 8, 1915. Serial No. 26,637.

To all whom it may concern:

Be it known that I, CHARLES H. WOODWARD, citizen of the United States, residing at Dallas, in the county of Dallas and State 5 of Texas, have invented certain new and useful Improvements in Stamp-Vending Machines, of which the following is a specification.

This invention relates to new and useful 10 improvements in stamp vending machines.

The object of the invention is to provide a machine for vending stamps and involving a circular carrier having a plurality of radial pockets of particular construction 15 adapted to carry stamps so that a portion of each stamp projects from the side or front of the carrier; together with a turning coin mover constructed to transmit rotation to the carrier through the agency of a coin de- 20 posited in the mover.

Another feature is means for retarding the rotation of the carrier; while another is means for limiting the turning movement of the coin mover.

25 Among other novel features are the provision of means for deflecting falling coins from the stamps and preventing the displacement of the stamps by the coins; means for locking the machine when empty and 30 preventing the further insertion of coins into the coin chute; means for conveying improper coins from the machine without operating the latter; means for positively returning the coin mover so that its coin re- 35 ceiving slot will accurately register with the coin chute; the provision of a stamp ejecting slot and guide so disposed as to assure a positive delivery and preventing stamps passing the said slot and not being deliv- 40 ered; and the provision of a two piece stamp carrier having interlocking portions, which when assembled provide stamp pockets in a simple and practical manner.

A still further object of the invention is 45 to provide a machine of the character described that will be strong, durable, efficient, and simple and comparatively inexpensive to construct, also one in which the several parts will not be likely to get out of 50 working order.

With the above and other objects in view the invention has relation to certain novel features of construction and operation, an example of which is described in the fol-

lowing specification and illustrated in the 55 accompanying drawings, wherein:

Figure 1 is a front elevation of the machine with the front cover wall removed, Fig. 2 is a longitudinal vertical sectional view, the stamp carrier and coin mover being omitted. Fig. 3 is a transverse vertical sectional view taken on the line $x-x$ of Fig. 1, the interior parts of the machine being illustrated in elevation, Fig. 4 is detail of one of the stamp carrier members, Fig. 5 is 65 a detail of the other carrier member, Fig. 6 is a detail in section showing the manner in which the stamps are presented and ejected, Fig. 7 is a detail showing the coin mover stop and illustrating the operation of 70 the coin mover, Fig. 8 is a sectional detail of the coin mover and component parts, and Fig. 9 is a detail in elevation of a portion of the front wall of the casing.

In the drawings the numeral 1 designates 75 the flared base of a metal casing which comprises a back wall 2, end walls 3 and 4 and a top wall 5. A removable front wall 6 for the casing has vertical inside ribs 8 adjacent each edge terminating in hinge lugs 7 en- 80 gaging in slots 9 in the top wall 5. The ribs abut the inner sides of the end walls and prevent lateral displacement of the wall 6; while the lugs hooked into the slots, as is best shown in Figs. 2 and 3, hold the upper 85 end of said wall 6 in place and permit it to be swung outward and removed. The lower end of the front wall is secured by a lock 10.

From the central portion of the back wall 2 a fixed stub shaft 11 projects inward and 90 has at its base a shoulder 12. A stamp carrying disk 13 is mounted to rotate on the shaft and bears against the shoulder which spaces it from the rear wall. The disk is held in place and its rotation retarded by an 95 arched spring plate 14 confined on the shaft by a cotter pin 15 piercing the shaft. The ends of the spring plate bear on the disk and hold the latter against the shoulder 12, whereby sufficient friction is had to offer 100 enough resistance to hold the disk to the position to which it is moved and to prevent overthrowing.

The disk or carrier 13 is composed of two members A and B and these will be de- 105 scribed in detail later in this specification. On the front of the member A means for rotating the disk is provided in the nature

of a gear ring 16 which is positioned concentric to the axis of the disk and is preferably formed integral therewith. The ring 16 is intermediate the stamp carrying means 5 of the disk and its center and the teeth are sufficiently spaced to permit a coin swung at right angles to the front of the disk to enter between two adjacent teeth, rotate the disk a limited distance, and freely pass out 10 of the ring.

For manipulating the disk or carrier a coin mover 17 is mounted to turn in the wall 3 of the casing and projects into the casing in a horizontal plane at right angles 15 to the stub shaft 11 in such near relation to the carrier that a coin held in the mover will engage in the gear ring 16 when said mover is turned toward the carrier. The inner end of the carrier is reduced to form 20 a spindle 18 which bears in a transverse aperture 19 in the shaft 11, the shoulder of the mover preventing inward longitudinal displacement of the mover.

The mover extends through the wall 3 25 and has fixed on its end outside of the casing a knob 20 which the operator may grasp in turning the mover. A coiled spring 22 has one end secured in the mover and the other end fastened to the wall 3. This 30 spring is disposed against the inner side of said wall 3 and prevents outward longitudinal displacement of the mover and said spring is so wound as to exert its tension in a direction opposite to that in which the 35 mover is turned in operation, whereby said mover is returned to its normal position when released.

A downwardly contracted slot 21 is provided in the mover and when the latter is 40 normal the slot occupies a true vertical position. This is due to a stop and limiting pin 23 inserted in the mover and projecting on each side thereof so as to engage under the cotter pin 15 to hold the mover in its 45 normal position, and to strike with its opposite end on top of the cotter pin and limit the rotation of the mover. The slot 21 is of such proportions as to receive and support a coin of certain diameter, but to 50 permit the passage therethrough of coins of smaller diameters. Directly under the slot 21 is a discharge tube 24, curved and directed through the wall 3 to a cup 25 mounted on the outside of said wall. A 55 smaller coin inserted in the machine will drop through the slot and be returned to the operator by way of the tube 24 and cup 25.

A coin of proper diameter and value received in the slot 21 projects sufficiently 60 from the mover to engage one of the teeth of the ring 16 when said mover is rotated toward the disk, thus imparting rotation to the disk, and to pass from between the 65 teeth as the mover reaches the end of its

rotation. It is to be understood that the disk carries postage stamps which project from the front side thereof and are arranged in groups spaced in harmony with the spacing of the gear teeth so that each 70 partial rotation of the disk brings a group of stamps to the vending point. After the coin passes out of the gear teeth it will drop from the slot and fall to the bottom of the casing and to prevent said coin striking and dislodging any of the stamps from the carrier 13 a deflecting plate 26 is fastened on the bottom of the casing and extends upward. As is best shown in Fig. 3 75 the deflector is inclined toward the carrier 80 and terminates below the mover at a point beyond the radius of path of the turning coin. The coin falls on this plate 26 and is guided to the bottom of the casing.

The front wall 6 of the casing as well as 85 the front edges of the end walls 3 have angular portions at the part, said front wall having portions 27 and 28 respectively and the end walls 3 being shaped to snugly receive the same. The upper most portion 27 90 has only a slight inclination to the perpendicular and is in close proximity to the carrier 13. The angular portion 28 extends from the lower end of the portion 28 to the vertical panel of the front wall as shown 95 and from its upper portion a coin chute 29 depends, said chute having its opening in the upper side of said portion 28 of such size as to exclude coins of larger diameters than that required to operate the machine. 100

The coin chute terminates just over the slot 21 of the coin mover and has one side cut out as shown at 3 so that the coin when resting in the slot will still project into the chute and while it may be swung toward the 105 disk, cannot be swung away from the disk on account of the solid wall opposite the cut away portion 33. In one side of the coin chute an aperture 30 is provided and a spring arm 31 having one end fastened to the 110 front wall 6 has its free end resting on the chute adjacent the aperture 30. A pin 32 projects from the front of the disk or carrier and the arm is in the path of this pin so once during the rotation of the carrier 115 the pin will strike the free end of the arm and carry it over the aperture into which it will spring. The end of the arm projecting in and across the chute will prevent the passage of coins therethrough, thus indicating that the machine is empty and preventing further operation until it is again filled with postage stamps and the spring arm withdrawn from the aperture 30. 120

We now will describe the details of construction of the carrier or disk 13 and the means for ejecting the stamps. As shown in the drawings the carrier has plurality of radial pockets 34 and considerable difficulty was experienced in producing in a 125 130

commercial and practical manner, a carrier provided with these pockets in such regular order and position as to coöperate with the gear ring and the coin mover in bringing the stamps to the same ejecting point at each operation; also so as to not carry the stamps past the ejecting point and to present them to the ejecting slot at the proper angle. In carrying out this construction 5 the carrier is composed of two members A and B, here-in-before referred to, and these members are of such configuration that they may be easily cast from patterns.

The member A comprises a round plate 10 portion 35 as is best shown in Figs. 1 and 5. Fingers 36 project radially from the periphery of the portion 35 in spaced order, each having one transverse face 37 at right angles to the vertical plane of the member 15 and the other transverse face 38 extending therefrom at angle of about forty degrees to said face; the faces meeting in a substantial knife edge 39 which is inclined toward its base as shown in Fig. 5. The 20 ring 16 projects from this member.

The member B takes the form of a ring and has recesses 40 conforming in shape to the fingers 36 and receiving the same. These 25 recesses are of such size as to provide a space or pocket between their walls and the faces 38 of the fingers whereby the pockets 34 are formed. Lugs 41 projecting inward from the member B have screw apertures 42 which register with similar apertures 43 in the portion 36 of the member A, whereby 30 the members are fastened together by screws 44 inserted in said apertures as shown in Fig. 1. When the members are assembled their front sides lie substantially flush 35 and the fingers fit in the recesses as shown.

The pockets being disposed at an angle as shown receive the stamps C as illustrated in Fig. 6 and present the same at an angle so that their vertical edges are substantially 40 parallel to the angular portion 27 of the wall 45 6. For guiding the stamps up to said portion 27 a guide plate 45 depends therefrom and has its lower end beyond the path of the stamps so that the latter are brought 50 into contact with the inclined face of the plate. Owing to the inclined disposition of the stamps due to the angles of the faces 38 and the edges 39, and the recesses 40 conforming thereto, said stamps are presented 55 to the guide plate at such an angle that one corner of each stamp first strikes the plate and is turned upward, whereby the balance of the projecting portion of each stamp is also turned up or forward as indicated in 60 Fig. 6.

For ejecting the stamps a slot 46 is provided in a reduced portion of the part 27 and is disposed at an angle to the perpendicular as shown best in Fig. 9 and which 65 is in harmony with the angle at which the

stamp is presented. It will be apparent that it would not be practical to have the slot 46 exactly vertical and the stamps held exactly in line with the radii of the carrier as the forward edge of the stamp must enter 70 said slot in advance of the arrival of the pocket at the slot, and further the stamps could not be turned forward if so presented to the guide plate.

The slot 46 has its far side, reference being 75 had to the approaching stamps, curved inward as indicated at 47 in Figs. 2, 6 and 9 to form an ejector against which the forward edges of the stamps impinge and are guided outward through said slot.

In operating the machine one desiring to purchase stamps drops a coin of the proper value in the chute 29 and grasps the knob 20. The coin is arrested in the slot 21 of the coin 80 mover 17 and has its upper portion projecting into the chute so that the mover cannot be turned away from carrier 13 for two reasons, first, the pin 23 engaging the pin 15, and then the solid wall of the chute. The open portion 33 of the chute permits the 85 mover 17 to be turned so that the coin is swung toward carrier and between two teeth of the gear ring 16, the coin acting as the tooth of a meshing pinion and imparting rotation to the carrier. The coin chute terminating so close to the slot 21 assures the 90 delivery of the coin to the same. After the mover has been turned a certain distance the coin is carried out of the ring and falls onto the deflector 26 by which it is guided to the 95 bottom of the casing. The operator now releases the knob and the spring 22 which has been wound during the rotation of the mover, returns the same to its normal position. The rotation imparted to the carrier 100 is sufficient to move the same the distance between two pockets 34 and eject the stamps of the following pocket through the slot 46 from which they may be readily removed. The operation may be repeated until the 105 machine is empty and the pin 32 strikes the 110 arm 31 and carries its free end into the aperture 30 which prevents further insertion of coins into the chute 29.

What I claim, is:

1. In a postage stamp vending machine, the combination of a vertical housing having an inclined slot disposed to deliver postage stamps, and a revoluble carrier mounted in the housing having a plurality of radial stamp pockets in its side disposed to pass in close proximity to the slot, each pocket being so constructed as to hold its stamp at an inclination to the vertical and transverse axes of the carrier, whereby said 120 stamp is presented to the slot of the housing with its advance side substantially parallel to said slot.

2. The combination in a postage stamp vending machine, of a casing having a ver- 125

tical stamp delivery slot disposed at an acute angle to the perpendicular, a guide plate mounted in the casing, and a vertical revoluble stamp carrier having a plurality of stamp pockets so constructed as to receive and present stamps at an angle to both the transverse and vertical axes of the carrier, said pockets presenting the stamps so that each stamp presents in advance one corner to the guide plate, whereby said stamp is curved forward and presented to the casing slot parallel thereto.

3. A stamp carrier for stamp vending machines comprising two members, one of said members having radial fingers with angular faces and the other member having recesses corresponding in shape to the fingers and receiving the latter, the said recesses being proportioned so that a stamp pocket is provided on one side of each finger.

4. A stamp carrier for stamp vending machines comprising two members, one of said members having radial fingers with angular faces and the other member having recesses corresponding in shape to the fingers and receiving the latter, the said recesses being proportioned so that a stamp pocket is provided on one side of each finger, and one of said members having provision for imparting rotation to the carrier.

5. The combination in a postage stamp vending machine, of a casing having a front wall provided with an inclined stamp delivery slot, a vertical revoluble stamp carrying disk mounted in the casing and having its upper portion in juxtaposition to the slot of the front wall of the casing, said disk having a plurality of stamp pockets in one side disposed at an angle to the radii of the disk and so constructed as to present

stamps from the side of the carrier at an angle to said side less than a right angle and in harmony with the inclination of the slot of the casing.

6. The combination in a postage stamp vending machine of a vertical casing having its front side open, a removable front wall mounted on the casing, the upper end of casing being retracted, said front wall having a stamp ejecting slot in its upper portion opposite the retracted portion of the casing, a rotatable vertical vending disk mounted in the casing so as to project into the retracted portion of the casing and having its front side passing in close proximity to the slot of the front wall, an ejector mounted on the front wall at the slot thereof, said disk having pockets constructed to present stamps at its side, said ejector projecting into the path of the stamps carried by the disk, whereby the stamps are deflected into the slot of the wall, means for retarding the rotation of the disk, and means for imparting rotation to the disk.

7. A stamp carrier for stamp vending machines comprising a disk-like structure having a plurality of radial recesses having their open sides coincident with the face of the structure, and fingers projecting into the recesses and disposed so that a stamp receiving pocket is provided at one side of each finger, each finger having its pocket side disposed at an angle intermediate the transverse and longitudinal axes of the structure, and the recesses each being correspondingly shaped whereby the pockets are likewise disposed.

In testimony whereof I affix my signature.

CHARLES H. WOODWARD.
